UNITED STATES PATENT OFFICE.

HOWARD GOODRICH, OF OMAHA, NEBRASKA.

DESIGN FOR A COSMETIC CHEST.

Application filed January 2, 1923. Serial No. 4,790. Term of patent 3½ years.

To all whom it may concern:

Be it known that I, HOWARD GOODRICH, a citizen of the United States, residing at Omaha, in the county of Douglas and State of Nebraska, have invented a new, original, and ornamental Design for a Cosmetic Chest, of which the following is a specification, reference being had to the accompanying drawing, forming a part thereof.

Fig. 1 is a top plan view of a cosmetic chest, showing my new design, and:

Fig. 2 is a side view of the same.

I claim:

The ornamental design for a cosmetic chest as shown.

In testimony whereof, I have affixed my signature in presence of two witnesses.

HOWARD GOODRICH.

Witnesses:

RUTH E. ANDERSEN,
A. H. MUNLOCK.
